H. HEINE, OF NEW YORK, N. Y.

Letters Patent No. 79,225, dated June 23, 1868.

IMPROVEMENT IN STEAM-GENERATORS.

The Schedule referred to in these Letters Patent and making part of the same.

TO ALL WHOM IT MAY CONCERN:

Be it known that I, H. HEINE, of the city, county, and State of New York, have invented a new and improved Steam-Boiler; and I do hereby declare the following to be a full, clear, and exact description thereof, which will enable those skilled in the art to which my invention appertains to fully understand, use, and make the same, reference being had to the accompanying drawings, forming part of this specification, in which drawing—

Figure 1 represents a vertical central section of this invention.

Figure 2 is a horizontal section thereof, the line $z z$, in fig. 1, indicating the plane of section.

Similar letters of reference indicate corresponding parts.

This invention relates to a steam-boiler, which is formed of two distinct parts, one inside of the other. The steam-dome of the inner or central part extends up through the centre of the outer or annular water-space, and the water and steam-spaces of both parts respectively communicate with each other through suitable pipes.

The fire-box of the central part is provided with a series of water-legs secured in the crown-sheet thereof.

The heated gases and products of combustion rising from the fire on the grate play round said water-legs, and escape, through apertures at or near the top of the fire-box, into a combustion-chamber formed on the outside of the central part, and between the same and the annular water-space which surrounds said central part. In this combustion-chamber the draught is downward, so that the fire comes in contact with the outer surface of the water-space which surrounds the fire-box, as well as with the inner surface thereof, thus increasing materially the effective heating-surface and insuring a complete combustion of the gases. This heating-surface is still further increased by a series of pipes secured to the outside of the central part and situated in the combustion-chamber formed between both parts. These water-pipes connect at their bottom ends with the lower part of the water-space of the central part, and from their top ends extend siphons into the water-legs, which are secured to the crown-sheet of the fire-box in such a manner that the hot water which rises in said water-legs is replaced by cooler water from the outside tubes, thereby insuring a perfect circulation of the water.

The combustion-chamber, as formed between the outside wall, or a part thereof, of the central part, and the inside wall of the annular water-space, and a diaphragm at or near the top of said annular water-space contracts, the products of combustion gradually as they descend in it, and the most so in that section where they leave the combustion-chamber in order to transmit as much heat as possible to those parts of the two parts which form the combustion-chamber.

From this combustion-chamber the gases pass through this annular water-space by means of fire-tubes provided in the same. The annular water-space is arranged so as to be readily detached from the central part for the purpose of repairing.

M represents the central part, of which A is the fire-box. In the bottom part of this fire-box is situated the grate B, and from its top or crown-sheet descends a series of water-legs, C. Said fire-box is surrounded by the water-space D, and above it rises the dome E, which communicates with said water-space and with the water-legs C, as shown in fig. 1 of the drawing.

The heated gases and products of combustion, which rise from the fire on the grate, are brought in direct contact with the inner wall of the water-space D and with the outer surfaces of the water-legs C, and they escape through apertures, a , at or near the top of the fire-box into the combustion-chamber F, which is formed between the central part, and the annular water-space G surrounding the same.

In this combustion-chamber the draught is downward, so that the fire comes in direct contact with the outer wall of the water-space D, whereby the effective heating-surface of the boiler is materially increased. This effect is still further increased by making the shape of the central and annular parts such that the combustion-chamber contracts toward the bottom end and becomes smallest where the gases escape therefrom.

On the outside of the central part, and in the combustion-chamber F, is secured a series of water-pipes, H, which communicate at their bottom ends with the water-space D; and at their top ends with the lower part of the dome E. As the fire descends in the combustion-chamber, it plays round these water-pipes, and the effective heating-surface is still further increased.

The water-pipes H are connected with the water-legs C by means of siphons, b, the long legs of which extend nearly down to the bottom of said water-legs, so that the hot water which rises in said water-legs by the action of the heat will be replaced by cooler water descending through the siphons, thereby insuring a complete circulation of the water.

In practice, these siphons will be made in two parts each, so that they can be readily taken out for the purpose of cleaning.

The top of the combustion-chamber F is closed by a diaphragm, p, which extends between the central part and the annular water-space. By these means the gases are forced downward in the combustion-chamber, and, according to the shape of the annular water-space, they have either to pass through the same or round it before they pass off through the chimney.

Said annular water-space G may be arranged, as represented in the drawing, with fire-tubes, c, which extend through it from end to end, and form the channel for the gases, or this annular water-space may be made without those fire-tubes, c, and may then be surrounded by a casing, with a space left between it and the annular part, which space will then be the channel for the gases passing up toward the chimney. In either case the steam-room or top of the annular water-space G is connected to the dome E of the central part by one or more pipes, said steam-dome being made to extend up through the centre of the annular water-space.

The water is admitted through the feed-pipe d to the annular water-space G, and passes over to the water-space D of the central part by means of one or more pipes, e, as shown in the drawing.

These pipes e reach up part way in the annular water-space, so that the hottest and cleanest water only can pass over to the central part, and the sediment is kept back in the former, and by this arrangement a perfect and positive circulation of the water is obtained, not only in the annular water-space G, but also in the central part M.

The annular water-space is arranged, in its connection with the central part, in a manner that it can be detached from it very easily. The annular water-space G is covered up by a bonnet, I, from the top of which rises the smoke-stack J.

By these means a steam-boiler is obtained which contains a very extensive heating-surface, and which also insures a perfect combustion of the fuel.

Having thus described my invention, what I claim as new, and desire to secure by Letters Patent, is—

1. A steam-generator, composed of an internal main or central part, M, and of an outer annular water-space, G, said internal part being provided with a water-space, D, and fire-flues, a, and communicating with the outer annular water-space by pipes e and g, all as shown and described.

2. The steam-dome E, rising through the centre of the bonnet I, which covers up the annular water-space G, said water-space and steam-dome being connected by pipes, g, substantially as and for the purpose set forth.

3. The water-pipes H, situated in the combustion-chamber F, between the central part and the annular water-space, substantially as and for the purpose set forth.

4. The siphons b, connecting the pipes H and the water-legs C, substantially as and for the purpose described.

This specification signed by me, this 8th day of April, 1868.

H. HEINE.
